FIG. 1 is a front perspective view of a medical lubricant tube support stand and tube sealing arrangement therefor showing my new design;

FIG. 2 is a right side view thereof, the left side being identical thereto;

FIG. 3 is a front end view thereof;

FIG. 4 is a back end view thereof;

FIG. 5 is a bottom plan view thereof;

FIG. 6 is a top plan view thereof;

FIG. 7 is a sectional view along the line 7-7 of FIG. 6 illustrating the inside face of the front end thereof;

FIG. 8 is a front elevation of a second modified embodiment of the support stand illustrated in FIG. 1, with portions partially shown in section;

FIG. 9 is a view along the line 9-9 of FIG. 8;

FIG. 10 is a view along the line 10-10 of FIG. 8;

FIG. 11 is a front elevation of a third modified embodiment of the support stand illustrated in FIG. 1 with portions partially shown in section;

FIG. 12 is a view along the line 12-12 of FIG. 11;

FIG. 13 is a view along the line 13-13 of FIG. 11;

FIG. 14 is a front elevation of a fourth modified embodiment of the support stand illustrated in FIG. 1 with portions partially shown in section;

FIG. 15 is a sectional view along the line 15-15 of FIG. 14;

FIG. 16 is a sectional view along the line 16-16 of FIG. 14;

FIG. 17 is a front elevation of a fifth modified embodiment of the support stand illustrated in FIG. 1 with portions partially shown in section;

FIG. 18 is a view along the line 18-18 of FIG. 17; and

FIG. 19 is a view along the line 19-19 of FIG. 17.

The dotted line showing of a tube cap mounted on the threaded support stud in FIGS. 15, 16 and 18 and the cap disclosed in FIG. 19 is for illustrative purposes, the tube cap not forming a part of the claimed design.

I claim:

The ornamental design for a medical lubricant tube support stand and tube sealing arrangement therefor, as shown and described.
